AIR HUMIDIFIER

Filed Sept. 24, 1926

INVENTOR

Robert W. Haudie. INVENTOR

UNITED STATES PATENT OFFICE.

ROBERT W. HARDIE, OF FANWOOD, NEW JERSEY

AIR HUMIDIFIER.

Application filed September 24, 1926. Serial No. 137,584.

This invention relates to means for increasing the relative humidity of an indoor atmosphere by adding steam or vapor thereto.

5 The term vapor is used herein in the same sense as that used by heating and ventilating engineers, that is steam, at about, or under, eight ounce pressure.

When steam above eight ounce pressure is 10 added to an indoor atmosphere, it has a strong tendency to condense near the point of discharge, on objects adjacent thereto.

Vapor, on the other hand is readily absorbed by an indoor atmosphere without 15 condensing.

But difficulties arise in raising vapor from a generator located in a basement, to an upper floor, and in carrying the vapor along horizontally extending mains or pipes 20 because of its lack of power to readily overcome atmospheric pressure.

In consequence thereof the vapor moves sluggishly, and has a tendency to remain in the generator, and difficulty is experienced 25 in discharging the vapor from the generator, and in carrying it to the place of discharge.

This tendency for the vapor, under or at eight ounce pressure to remain in the generator, also prevents the production of vapor 30 in the desired quantities.

If on the other hand vapor can be quickly removed from the generator, and from the surface of the water therein, the quantity 35 of vapor produced can be largely increased within a given time.

The main objects of the invention are to provide means for generating vapor in the most facile, and economical manner, and in 40 the shortest time possible, and to carry the vapor to the desired place of discharge as quickly as possible, and enable the vapor to be discharged into an indoor atmosphere, and absorbed without condensation.

45 These and other objects of the invention are accomplished by the means hereinafter described, and illustrated in the accompanying drawings, wherein is shown a preferred embodiment of the invention as applied for

producing vapor, but which may be readily 50 changed into a device for producing and discharging steam into an indoor atmosphere.

It will be understood, however, that changes, alterations and modifications may 55 be made therein without departing from the invention.

The accompanying drawing represents a device used in carrying out the invention, showing a water containing tank having a 60 closed top, and a supporting base in cross section; a gas burner, and pipe connections, and a vapor discharge head and pipe connections, in side elevation; and means for supplying water to the tank, partly in side 65 elevation and partly broken away.

As illustrated in the drawings, 1 represents a supporting base, circular in outline, provided with a door 2, and with air inlets 3, and preferably with a bottom 4, which 70 may be connected with the shell of the base in any suitable manner as by means of a flange 5 secured to the inturned lower margin 6 of said shell.

The base is also provided with a tubular 75 discharge connection 7 to permit the products of combustion to pass out of the interior of said base.

The water tank 8 may be supported upon a base or support of any suitable construction, but as shown in the drawings, the flange 9 of the bottom 10 of the tank and the adjacent portion of said bottom, bear upon and engage the upper margin of the base 1.

The water inlet pipe 11 is connected with the bottom of the tank and with a branch 12, which is connected with a discharge valve 13 and with a pipe 14 leading to a water bowl 15.

This water bowl is provided with an inlet valve, and a float 16 of ordinary construction.

The inlet valve is connected with the water supply of a house by means of a nipple 17, in the usual manner.

By means of such construction, water from a source of supply is furnished to the

interior of the bowl and to the interior of the tank 8, and is maintained at a constant level by means of the float 16, automatically opening and closing the valve of the water bowl in the usual manner.

When the device is in use, the valve 13 is kept closed, but when it is desired to withdraw the water from the interior of the tank the valve is opened and the water discharged therefrom.

A stud or bar 18 is secured to the bottom or lower head of the tank, and is connected at its lower end with a gas burner 19 by means of a T 20 or otherwise. The burner 19 is connected with the gas supply pipe of a house by means of piping 21.

Such construction provides effective means for holding the gas burner in proper position relative to the lower head of the tank, and at a proper distance therefrom, and permits the parts to be quickly and accurately assembled.

The gas supply piping 21 is provided with a hand operated cock 22, of any suitable or ordinary construction. Said piping is also preferably provided with a gas pressure control or governor, in the form of a gas cock 23, having a square head or other means to prevent the valve of said cock from being inadvertently changed after having been set to deliver the desired quantity of gas to the burner.

I do not desire to be limited to a gas cock as a gas pressure control or governor for regulating and controlling the desired maximum quantity of gas to the burner.

Any other known device having the capability of so doing, may be used instead of said cock if desired.

The quantity of gas to be supplied to the burner 19 depends upon the quantity of water within the tank, and the temperature at which it is desired to maintain the water, and the quantity of vapor or steam desired to be discharged.

By using two valves, the valve 23 with its square head may be set by means of a wrench, and not by the fingers of the hand. The valve 22 may be operated by hand, and kept wide open if desired when the device is in operation, and entirely closed when the device is not in operation, and need not be adjusted every time the gas is turned off, as would be the case if only the valve 22 is used.

A T 24 or other suitable means, is connected with the upper head of the tank and suitable piping 25 is connected with said T, and with a discharge head, which is designed to be located on the first floor of a building, while the apparatus itself is designed to be located in a basement.

In the construction shown, the discharge head consists of a supporting member 26

preferably having a threaded connection 65 with the piping 25, and with tubular sections 27 which are closed at their outer ends and provided with apertures 28.

The tubular sections 27 are preferably made adjustable axially relative to the central sections 26 by means of a threaded connection therewith, and discharge openings 28 may thereby be arranged at the top or the side of said sections.

These sections being tubular in construction, provide a smooth interior with substantially straight longitudinal lines, and thereby reduce frictional resistance to the passage of the vapor, and also provide a smooth unobstructed lower inner surface to permit the water of condensation that forms in the discharge head to readily pass back into the interior of the tank.

The upper head of the tank is also preferably provided with an air inlet, which may be of any desired construction, but as shown herein consists of a threaded opening provided with a short nipple 29 and a wire screen, or perforated disk 30, placed upon the end of the nipple with an open cap 31 90 having a threaded engagement with the nipple 29 and provided with an inner flange engaging the outer margin of the disk 30 and the upper end of the nipple 29.

I have discovered that if the temperature of the water within the tank is maintained 210° F. or less, so as to produce vapor, and not steam, and two discharge connections are made with the upper end of the tank, and a discharge head is connected with each connection so as to permit one discharge head to be placed in one room, and another discharge head in another room, vapor will pass up through the pipe that happens to be the warmer, and out through the discharge head connected with that pipe, and no vapor will pass out through the other pipe connected with the upper end of the tank.

I have also discovered that if but one of the openings formed in the upper head of the tank is provided with a discharge head, and discharge pipe, and the other opening is closed with a plug as shown in Letters Patent granted to me June 16, 1925, Number 1,542,696, and the water in the tank is maintained at 210° F. or lower, the vapor will not pass freely from the interior of the tank through the discharge pipe and discharge head, the vapor will pass out sluggishly, and clog up the interior of the tank.

Therefore I use one of the openings in the upper end of the tank as an air inlet.

In such construction air passes into the interior of the tank through said opening and across the interior of the tank, thereby creating a circulation of air within the tank that forces the vapor from off the surface of the water, and out of the tank,

and permits the production of vapor to be increased within a given time and discharges the vapor quickly into the atmosphere from the interior of the tank.

5 If more than one discharge pipe or head is desired, the plug shown connected with the T 24 may be removed, and one or more discharge pipes and heads be connected with said T.

10 When it is desired to use the device for producing steam above eight ounce pressure, the vent 29 is closed by means of a plug or otherwise.

15 The only way the relative humidity of an indoor atmosphere can be increased is, by adding vapor of water thereto.

20 One of the greatest problems to be solved in so doing consists in devising means or methods for delivering the vapor of water into an indoor atmosphere in such a manner and in such condition that the vapor will be readily and quickly absorbed by such an atmosphere, and not condense on objects in the immediate vicinity of the place of discharge.

25 To accomplish that end the general practice heretofore followed has been to first mix the vapor with a relatively small quantity of air, to partially diffuse the vapor, and then deliver the mixed vapor and air into the indoor atmosphere.

30 Various methods and means have been employed for so doing. In some instances vapor is mixed with a preliminary quantity of air at the same time the vapor is produced, and in other instances the vapor after being produced is discharged into an enclosure, box or flue that serves as a mixing chamber and from there delivered into the indoor atmosphere.

40 One of the results produced by the present invention is that vapor is thereby discharged directly into an indoor atmosphere in such a manner and in such condition as not to require such preliminary mixing of the vapor with air and at the same time avoiding condensation.

45 In order to discharge vapor into an indoor atmosphere without preliminary mixture of the vapor and air, the vapor is produced, by the present invention, from water heated at a temperature not higher than 212° F. and at atmospheric pressure.

50 Vapor so produced is not heavily laden with water and is readily absorbed by an indoor atmosphere without any preliminary mixing with air.

55 Mechanical devices are required to produce the vapor, but they can not ordinarily be located in the rooms of a house or building that are used for living or business purposes.

60 Means must therefore be employed to carry the vapor when produced, from the

place where the generating apparatus is located to the place of discharge.

65 Vapor developed at atmospheric pressure and at a water temperature of not more than 212° F. has no carrying power of itself and no pressure back of it. It remains sluggish 70 on, and over, the surface of the water, and by blanketing the water prevents new vapor from readily arising from that surface. It can not lift itself from the basement of a building where the generator is placed to a 75 floor above, nor can it flow laterally in the basement.

80 If the vapor is developed under pressure greater than that of atmosphere and from water at a higher temperature than 212° F., it has carrying power by virtue of the pressure back of it, and can travel vertically and laterally. But that is steam and not vapor as the terms are used herein, and the steam is 85 laden with grains of water to such an extent that it will condense on objects near the place of its discharge, and therefore is not in fit condition to be absorbed in an indoor atmosphere.

90 When the device is in operation, the upper portion of the tank and the discharge pipe connected therewith become heated by the water in the tank, the air within the discharge pipe then becomes heated and rises, thereby inducing an upward flow of air and 95 vapor within the pipe.

100 Air from outside then enters the tank, through the inlet opening, and passes across the surface of the water in the tank carrying the vapor from off the surface of the water and up through said pipe and out of the discharge head, thereby permitting new vapor to arise freely and quickly from the surface of the water.

105 As the air and vapor pass through the discharge pipe and head a slight rise of pressure is produced in the pipe and head, by means of the restricted openings in the discharge head, thereby aiding in carrying the vapor vertically from the tank in the basement to a floor above, or laterally as may be desired.

110 In the construction shown herein the tank 8 is shown supported upon the casing of the combustion chamber.

115 That, however, is not an essential feature of the invention, and any other suitable means may be employed for supporting the tank.

120 What I claim as new is:

1. An air humidifier comprising a closed water containing tank provided with an air inlet and a vapor discharge outlet, a discharge pipe connected with said outlet, a discharge head provided with restricted 125 apertures connected with said discharge pipe, means for supplying water to said tank, and means for heating said water.

2. An air humidifier comprising a closed water containing tank provided with an air inlet on one side of the axial line of said tank, and a vapor discharge outlet on the opposite side of said axial line, a discharge pipe connected with said outlet, a discharge head provided with restricted apertures, connected with said discharge pipe, means for supplying water to said tank, and means for heating said water. 65
3. An air humidifier comprising a closed water containing tank provided with a shielded air inlet and a vapor discharge outlet, a discharge pipe connected with said outlet, a discharge head provided with restricted apertures connected with said discharge pipe, means for supplying water to said tank, and means for heating said water. 70
4. An air humidifier comprising a closed water containing tank provided with an air inlet having a shield detachably connected therewith, and a vapor discharge outlet, a discharge pipe connected with said outlet, a discharge head provided with restricted apertures connected with said discharge pipe, means for supplying water to said tank, and means for heating said water. 75
5. An air humidifier comprising a closed water containing tank provided with an air inlet, opening directly into the atmosphere, and a vapor discharge opening, means connected with said discharge opening for connecting a plurality of discharge pipes with said opening, a discharge pipe connected with said means, a discharge head provided with restricted discharge openings connected with said discharge pipe, means for supplying water to said tank and means for heating said water. 80
6. An air humidifier comprising a closed water containing tank having a vapor discharge opening, a discharge pipe connected with said opening, a discharge head connected with said pipe comprising a supporting member and horizontally extending apertured tubular members, having an unobstructed lower inner surface and axially adjustable on said supporting member, means for supplying water to said tank, and means for heating said water. 85
7. An air humidifier comprising a closed water containing tank having a vapor discharge opening, a discharge pipe connected with said opening, a discharge head comprising a T connected with said restricted discharge pipe and horizontally extending tubular members having closed ends and a threaded connection with said T, and provided with restricted apertures and with a closed uninterrupted inner under surface, means for supplying water to said tank, and means for heating said water. 90
8. An air humidifier comprising a closed water containing tank having a vapor dis- 95
- charge opening, a discharge pipe connected with said opening, a discharge head connected with said discharge pipe and comprising horizontally arranged distributing members provided with restricted discharge apertures, and an uninterrupted lower inner surface, means for supplying water to said tank and means for heating said water. 100
9. An air humidifier comprising a closed water containing tank having a vapor discharge opening and an air inlet, means for maintaining a constant quantity of water within said tank, a gas burner beneath said tank, a pipe connection leading from said burner to a source of gas supply, and means within said connection for controlling and governing the maximum quantity of gas supplied to said burner. 105
10. An air humidifier comprising a closed water containing tank having a vapor discharge opening and an air inlet, means for maintaining a constant quantity of water within said tank, a gas burner beneath said tank, a pipe connection leading from said burner to a source of gas supply, a governor within said connection for regulating and maintaining a maximum pressure of the gas supplied to said burner, and a shut off cock in said connection for opening and closing said connection. 110
11. The method of humidifying air, consisting in maintaining a constant quantity of water within a closed container, converting said water into vapor by applying a heating element thereto while maintaining the water at a temperature not exceeding 212° F., causing a current of air to pass from outside into said container and mix with said vapor, conducting said air and vapor through a conduit, and delivering said air and vapor from said conduit into the atmosphere in restricted quantities. 115
12. The method of humidifying air consisting in maintaining a constant quantity of water within a closed container, converting the water into vapor by applying a gas heating element thereto while controlling the maximum pressure of said gas heating element, causing a current of air to pass from outside into said container and mix with said water, conducting a quantity of said vapor and air to a place of discharge, and delivering said quantity of air and vapor into the atmosphere in restricted quantities. 120
13. The method of humidifying air consisting in maintaining a constant quantity of water within a closed container, converting said water into vapor by the application of a heating element thereto while maintaining the water at a temperature not exceeding 212° F., causing a current of air to pass from outside into said container and mix with said vapor, conducting said air and vapor through a conduit and delivering said 125

air and vapor into the atmosphere in restricted quantity under a pressure slightly above the pressure in the interior of the container.

5 14. The method of humidifying air, consisting in maintaining a constant quantity of water within a closed container, converting the water into vapor by applying a gas heating element thereto, controlling the
10 maximum quantity of gas applied to said

water, while permitting variations in quantity of gas supplied below said maximum, causing a current of air to pass from outside into said container and mix with said vapor, leading a quantity of said mixed air and vapor through a conductor to a place of discharge, and discharging said vapor and water into the atmosphere in restricted quantities.

ROBERT W. HARDIE.
